RAIL TIE

Application filed April 11, 1930. Serial No. 443,303.

This invention relates to new and useful improvements in a rail tie.

The invention has for an object the provision of a device of the class mentioned which is of simple durable construction, dependable in use and efficient in action, and which can be manufactured and sold at a reasonable cost.

The invention proposes a body member for extending transversely beneath a pair of rails and formed with a pair of end elements for engaging on the outer sides of said pair of rails, a pair of bosses positioned for location adjacent the inner sides of said rails, and side walls connecting said end elements, plates extended across said side walls and over the bosses, jaw plates on said plates and abutting against the inner sides of said rails, means for holding said jaw plates in place, pegs projecting from said jaw plates and engaging in apertures in said rails, and lugs projecting from said side walls and extending partially over the jaw plates from the inner sides for aiding in holding the jaw plates in place.

The invention also proposes that said lugs be slideable on the side walls and means be provided for adjustably holding said lugs, and fingers project from the lugs and in operative positions of the lugs latch the said means which hold the jaw plates.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

Fig. 1 is a plan view of a rail tie constructed according to this invention and shown applied to a pair of rails.

Fig. 2 is a vertical sectional view taken on the line 2—2 of Fig. 1.

Fig. 3 is a vertical sectional view taken on the line 3—3 of Fig. 2.

Fig. 4 is a perspective view of one of the inverted plates used in the rail tie.

Fig. 5 is a perspective view of one of the jaw inverted plates used in the rail tie.

Fig. 6 is a fragmentary view similar to a portion of Fig. 2, but illustrating a modified form.

Fig. 7 is an enlarged fragmentary sectional view taken on the line 7—7 of Fig. 6.

The rail tie consists of a body member 10 for extending transversely beneath a pair of rails 11 and formed with a pair of end elements 12 for engaging the outer sides 13 of said rails 11, a pair of bosses 14 positioned for location adjacent the inner sides of said rails, and side walls 15 connecting said end elements, plates 16 extended across said side walls 15 and abutting against the inner sides of the rails 12, means for holding jaw plates 17 in place, pegs 18 projecting from said jaw plates 17 and engaging in apertures in said rails, and lugs 19 projecting from said side walls 15 and extending partially over said jaw plates 17 from the inner sides for aiding in holding the jaw plates in place.

The body member 10 also includes a flat base 20 adapted for resting upon a railroad bed. The end elements 12 have inclined tops 21 and the inner sides 22 are so shaped as to fit the contour of the rail. The plates 16 have bottom ribs 23 arranged to abut against the side walls 15 for maintaining their transverse positions. The jaw plates 17 have their outer sides of a contour to fit the contour of the inner sides of the rails.

The means for holding said jaw plates in place comprises headed pins 24 passing thru the jaw plates 17, the plates 16 and into the bosses 14. The heads 25 of the pins 24 rest upon the jaw plates 17. A wedge 26 passes thru the side walls 15, the bosses 14, and the pins 24 for holding the pins in place. The rails 11 are shown formed of rail sections 11^a slightly spaced from each other for accommodating expansion. The pegs 18 engage upon opposite sides of the space, that is, one peg engages each of the rail sections. The outer sides of the lugs 19 are formed with a vertical portion for abutting against the inner sides of the plates 16 and the jaw plates 17, and with overhanging top elements 100

28 for resting upon the tops of the jaw plates 17.

5 In the modified form of the device illustrated in Figs. 6 and 7, the lugs 19 have been shown slidably arranged upon the side walls 15. Each of the lugs 19 is formed with a dovetailed tongue 29 engaged in a dovetailed groove in the side wall so as to accomplish the slideable mounting. A rack 30 projects 10 from the tongue 29 and engages against a worm 31 rotatively mounted within a cavity 32 in the side wall. A gear 33 connects with the worm 31 and is reachable thru an opening 34 in the side wall. Dot and dash lines 15 35 in Fig. 7 indicate a gear in mesh with the gear 33 and rotatively supported upon a journal 36. Normally the journal 36 and the gear 35 is not attached upon the side wall, but only in the event that it is desired to dis- 20 engage the lugs 19. A finger 37 projects from the tongue 29 and extends from the cavity 32 and is extendable thru an opening in the boss 14 and in the pin 24.

25 In operation of the device, the wedge 26 may be removed so that the pin 24 is loose which may also be removed. Then the jaw plate 17 and the plate 16 may be lifted from place so that the rail is loose and may be removed. The pegs 18 engage in the apertures 30 of the rails when the rail tie is assembled and hold the rail against longitudinal movements. The end elements 21 and the jaw plates hold the rails against transverse movements.

35 In the form shown in Figs. 6 and 7, the fingers 37 supplement the action of the wedges 26 for holding the pins 24 in place. Before the pins may be removed, it is necessary that the gears 33 be rotated so that the lugs 19 move away from the jaw plates, simultaneously moving the fingers out of engagement from the apertures in the pins 24. The gears 33 may be tightly turned to force the lugs against the sides of the jaw plates and the plates 16 for clamping the rails in place.

40 45 While we have shown and described the preferred embodiment of our invention, it is to be understood that we do not limit ourselves to the precise construction herein disclosed and the right is reserved to all changes and modifications coming within the scope 50 of the invention as defined in the appended claims.

Having thus described our invention, what we claim as new, and desire to secure by 55 United States Letters Patent is:—

1. A rail tie, comprising a body member for extending transversely beneath a pair of rails and formed with a pair of end elements for engaging the outer sides of said 60 pair of rails, a pair of bosses positioned adjacent the inner sides of said rails, and side walls connecting said end elements, plates extended across said side walls and over said bosses, jaw plates on said plates and abutting against the inner sides of said rails,

means for holding said jaw plates in place, pegs projecting from said jaw plates and engaging in apertures in said rails, and lugs projecting from said side walls and extending partially over the jaw plates from the inner sides for aiding in holding the jaw plates in place. 70

2. A rail tie, comprising a body member for extending transversely beneath a pair of rails and formed with a pair of end elements for engaging the outer sides of said pair of rails, a pair of bosses positioned adjacent the inner sides of said rails, and side walls connecting said end elements, plates extended across said side walls and over said bosses, jaw plates on said plates and abutting against the inner sides of said rails, means for holding said jaw plates in place, pegs projecting from said jaw plates and engaging in apertures in said rails, and lugs projecting from said side walls and extending partially over the jaw plates from the inner sides for aiding in holding the jaw plates in place, said body member having a flat base for resting upon a railroad bed. 75 80 85 90

3. A rail tie, comprising a body member for extending transversely beneath a pair of rails and formed with a pair of end elements for engaging the outer sides of said pair of rails, a pair of bosses positioned adjacent the inner sides of said rails, and side walls connecting said end elements, plates extended across said side walls and over said bosses, jaw plates on said plates and abutting against the inner sides of said rails, means for holding said jaw plates in place, pegs projecting from said jaw plates and engaging in apertures in said rails, and lugs projecting from said side walls and extending partially over the jaw plates from the inner sides for aiding in holding the jaw plates in place, said end elements having inclined tops and inner sides shaped to the rail contour. 95 100 105 110

4. A rail tie, comprising a body member for extending transversely beneath a pair of rails and formed with a pair of end elements for engaging the outer sides of said pair of rails, a pair of bosses positioned adjacent the inner sides of said rails, and side walls connecting said end elements, plates extended across said side walls and over said bosses, jaw plates on said plates and abutting against the inner sides of said rails, means for holding said jaw plates in place, pegs projecting from said jaw plates and engaging in apertures in said rails, and lugs projecting from said side walls and extending partially over the jaw plates from the inner sides for aiding in holding the jaw plates in place, said plates having bottom ribs for abutting against the side walls and holding the plates against transverse motions. 115 120 125 130

5. A rail tie, comprising a body member for extending transversely beneath a pair of rails and formed with a pair of end elements for engaging the outer sides of said pair of rails, a pair of bosses positioned adjacent the inner sides of said rails, and side walls connecting said end elements, plates extended across said side walls and over said bosses, jaw plates on said plates and abutting against the inner sides of said rails, means for holding said jaw plates in place, pegs projecting from said jaw plates and engaging in apertures in said rails, and lugs projecting from said side walls and extending partially over the jaw plates from the inner sides for aiding in holding the jaw plates in place, the means for holding said jaw plates in place comprising headed pins passed thru the jaw plates and two apertures in said bosses, and wedges thru the body member and thru said pins.

6. A rail tie, comprising a body member for extending transversely beneath a pair of rails and formed with a pair of end elements for engaging the outer sides of said pair of rails, a pair of bosses positioned adjacent the inner sides of said rails, and side walls connecting said end elements, plates extended across said side walls and over said bosses, jaw plates on said plates and abutting against the inner sides of said rails, means for holding said jaw plates in place, pegs projecting from said jaw plates and engaging in apertures in said rails, and lugs projecting from said side walls and extending partially over the jaw plates from the inner sides for aiding in holding the jaw plates in place, said lugs having vertical portions for engaging against the sides of the plates and jaw plates and overhanging top portions for engaging above the jaw plates.

7. A rail tie, comprising a body member for extending transversely beneath a pair of rails and formed with a pair of end elements for engaging the outer sides of said pair of rails, a pair of bosses positioned adjacent the inner sides of said rails, and side walls connecting said end elements, plates extended across said side walls and over said bosses, jaw plates on said plates and abutting against the inner sides of said rails, means for holding said jaw plates in place, pegs projecting from said jaw plates and engaging in apertures in said rails, and lugs projecting from said side walls and extending partially over the jaw plates from the inner sides for aiding in holding the jaw plates in place, said lugs being slidably mounted on the side walls, means being provided for adjustably holding the lugs, and fingers projecting from the lugs and in operative positions of the lugs engaging in apertures in pins included in the means for

holding the jaw plates in place for latching purposes.

In testimony whereof we have affixed our signatures.
